UNITED STATES PATENT OFFICE.

JOSEPH J. ROURKE, OF TERRE HAUTE, INDIANA.

SELF-ADJUSTING SAND-MOLD BOX.

Application filed November 13, 1924. Serial No. 749,635.

This invention relates to a box that is designed to be used in a foundry to reinforce a sand mold while molten metal is being poured into the mold, the invention 5 having reference more particularly to an adjustable sand mold box that is adapted to be used instead of a cover board and weights thereon, for holding down the top of a sand mold to resist the tendency of the 10 hot metal to cause rupture of the mold.

An object of the invention is to provide a sand mold box and weight, which shall be of such construction as to be adapted to be quickly applied and clamped to a sand 15 mold following the removal of a molding flask from the mold.

Another object is to provide an improved sand mold box which shall be of such construction as to be adjustable to a sand mold, 20 whether the side faces of the mold be vertical or slightly inclined, and which shall be adapted to prevent expansion of the mold both laterally and vertically, while eliminating the trouble and labor incidental 25 to placing heavy weights upon the sand mold with the flask on the mold.

A further object is to provide an improved sand mold box which shall be so constructed as to be adapted to be placed 30 on a sand mold after having been made in a snap flask, without injury to the sides of the mold when they are vertical, and also to eliminate the cost and trouble incidental to the production of molds having 35 inclined sides and a sand mold box of a rigid construction having slanting sides, necessitating the placing of weights upon the top of the box or clamps to hold the box in place, with no certainty of the box 40 having close contact with the top and sides of the mold; which improved mold box shall be of substantial and simple construction, easily and quickly handled, and durable and economical in use.

45 With the above-mentioned and other objects in view, the invention consists in an expandible or contractible mold box of novel construction adapted to operate automatically in response to the handling of the box 50 to place it in position for use or in removing it from a mold; and, the invention consists also further in the novel parts, and in the combinations and arrangements of parts, as hereinafter particularly described and 55 further more definitely defined and claimed hereinafter.

Referring to the drawings:—Figure 1 is a perspective view of the mold box constructed substantially in accordance with the invention, the several parts of the box 60 appearing as when the top is supported and the side parts hanging thereon; Fig. 2 is a side elevation of the box, the parts thereof being represented as when the side parts are supported on their bottoms; Fig. 3 is 65 a longitudinal central section partially broken away showing a sand mold and the box clamped thereto; and Fig. 4 is an end elevation partially broken away showing the mold box on the mold and nearly approaching the clamping position.

Similar reference characters in the several figures of the drawings indicate corresponding elements or features of construction herein referred to in detail.

As an aid to an understanding of the purposes and mode of operation of the invention, a sand mold is illustrated in the drawings and comprises a bottom part 1 and a top part 1', the complete mold having 80 a hollow form 2 therein assumed to have been molded by means of a pattern, the mold having a gate 3 to conduct molten metal to the mold form.

The self-adjusting mold box comprises a 85 metallic top slab 4 which is rectangular in plan and in some cases is oblong, the corners of the slab having projecting brackets 5, 6, 7 and 8 thereon respectively, the brackets being integral with the edge portions of 90 the slab as preferably constructed, and preferably the brackets extend downwardly from the slab and have "fish-tail" ends. The brackets have longitudinal guide wings 9, 10, 11 and 12 thereon respectively and 95 also transverse guide wings 13, 14, 15 and 16, respectively. Each guide wing is integral with its supporting bracket and extends downward therefrom, each bracket having a longitudinal and a transverse 100 wing thereon, the wings being integrally connected together and supported at right angles each to the other. Each guide wing has an inclined guide slot 17 therein that diverges upwardly in direction from the 105 adjacent wing and constitutes a cam or wedging device. Two side clamp plates 18 and 19 are provided which are alike and nearly as long as the top slab, and each plate has ears 20 and 21 on its outer side 110 adjacent to the ends thereof, the ears having guide pins 22 and 23 thereon respectively.

that extend through the slots in the adjacent transverse wings between which the clamp plate is guided. Two similar end clamp plates 24 and 25 are provided and each is arranged between two longitudinal guide wings and has ears 26 and 27 on its outer side adjacent to the ends thereof that are provided with guide pins 28 and 29 respectively which extend through the slots in the longitudinal guide wings adjacent thereto. One of the guide pins is sufficiently broad to prevent its rotation in the slot yet permitting slight tilting of the clamp plate, and both pins for each clamp plate may if so desired be likewise broader than the width of the slot. This permits the clamp plates to accommodate themselves to inclined mold sides as well as to vertical sides. The guide pins of the clamp plates serve the purpose of lugs, the pins on the end plates extending under the pins on the side plates, so that the side plates shall be lifted by means of the end plates, the end plates being provided with handles 30 and 30' respectively whereby they may be lifted.

Preferably the inner face of each clamp plate is suitably roughened or provided with cross ribs 31 adapted to slightly sink into the side faces of the sand mold under the pressure exerted on the plates, to secure the plates to the mold.

The top slab 4 has a suitable opening 32 therein permitting metal to be poured into gates in the mold.

In practical use the mold box is carried, lowered, and lifted by means of the handles on the clamp plates. Upon lifting the end plates they are carried upward relatively to the guide wings and they in turn lift the side clamp plates until stopped by the pins at the tops of the cam slots, enabling the clamp plates to lift the top slab. After a sand mold has been made the molding flask is removed from the mold, and the mold box is placed on the mold, the top slab resting upon the top of the mold, and the handles 30 on the end plates being released, all the clamp plates descend by the force of gravity and are forced by means of the cam slots against the surfaces of the sand mold, whereby the top slab is securely clamped to the mold instead of being clumsily held down as in common practise by means of heavy pieces of iron or stones. When the molten metal is poured into the mold the sand mold is protected by the self-adjusting box against distortion or fracture, so that the correct shape of the mold

form is maintained during the cooling of the metal in the mold, resulting in the production of superior castings. When the casting has become sufficiently cooled to hold its shape the mold box is lifted from the mold, and the mold may be broken up as usual to release the casting produced thereby.

What is claimed as new is:

1. A self-adjusting sand mold box including a top slab provided with projecting pairs of guide wings having each an inclined guide slot therein, and a plurality of clamp plates arranged between the wings of the pairs respectively and provided with lug pins movably extending through the slots in the wings. 75

2. A self-adjusting sand mold box including a top slab provided with depending guide wings having cam slots therein respectively to control clamp plates, and a plurality of clamp plates provided each with a pair of guide pins extending through the slots in a pair of the wings, the pins on two opposite plates extending under the pins on the remaining clamp plates to lift the latter plates. 80

3. A self-adjusting sand mold box including a top slab that is rectangular in plan and provided on the corners thereof with projecting brackets, each bracket having two relatively angular guide wings on the normally under side thereof, the slab having an aperture therein, and a plurality of clamp plates arranged below the edge portions of the slab, each plate having connections with two of the wings to guide the plate downwardly and inwardly or upwardly and outwardly relatively to the other plates and the slab. 95

4. A self-adjusting sand mold box including a top slab, a plurality of clamp plates to secure the slab in place on a mold, the plates being arranged under the edge portions of the slab and having each a pair of ears on the outer side thereof and gripping projections on the inner side thereof, two opposite ones of the plates having each a handle thereon, guiding means to adjustably connect the ears on the remaining clamp plates with the slab, and guiding and lugging means to connect the ears on the handled clamp plates with the slab and also with the other guiding means. 100

In testimony whereof, I affix my signature on the 1st day of November, 1924.

JOSEPH J. ROURKE.
